UNITED STATES PATENT OFFICE.

EDWARD N. JACOBI, OF MILWAUKEE, WISCONSIN, ASSIGNOR TO BRIGGS & STRATTON CORP., OF MILWAUKEE, WISCONSIN, A CORPORATION OF DELAWARE.

LOCK.

Application filed March 25, 1929. Serial No. 349,159.

This invention relates to certain new and useful improvements in locks and has as an object to provide novel means for protecting the lock cylinder against destruction and for 5 maintaining the lock cylinder assembled with its mounting member.

Another object of this invention resides in the provision of an enlarged head formed on the outer end of the lock cylinder and which 10 is enclosed by a correspondingly shaped protecting hood to facilitate turning of the lock cylinder independently of the key.

Another object of this invention resides in the provision of a novel lock construction of 15 the character described in which a protecting hood encloses the outer end of the lock cylinder and the mounting member to prevent destruction thereof and whose inner portion is provided with novel means to be clinched 20 over a stop formed in the mounting member to prevent detachment of the cap and removal of the lock cylinder.

A further object of this invention resides in the provision of a lock device in which destruction of the lock cylinder is prevented by 25 a protecting hood stamped from hardened bendable metal and whose inner end is clinched at intervals to engage a stop formed on the mounting member, and said protecting 30 hood being apertured adjacent the clinched portions whereby the clinching may be accomplished without causing binding between the hood and the mounting member.

And a still further object of this invention resides in the provision of a lock device in 35 which the lock cylinder is provided with an enlarged irregularly shaped head at its outer end over which a protecting hood is engaged whose inner end is freely rotatably connected 40 with the mounting member to prevent separation of the protecting hood and the lock cylinder from the mounting member and to provide means for turning the lock cylinder independently of its key.

With the above and other objects in view 45 which will appear as the description proceeds, my invention resides in the novel construction, combination and arrangement of parts substantially as hereinafter described 50 and more particularly defined by the appended claims, it being understood that such changes in the precise embodiment of the hereindisclosed invention may be made as come within the scope of the claims.

55 In the accompanying drawing, I have il-

lustrated one complete example of the physical embodiment of my invention constructed according to the best mode I have so far devised for the practical application of the principles thereof, and in which:

Figure 1 is a view, part in elevation and part in section, illustrating a lock device embodying my invention;

Figure 2 is a cross sectional view taken through Figure 1 on the plane of the line 65 2-2;

Figure 3 is a perspective view of the mounting member;

Figure 4 is a perspective view of the lock cylinder, and

Figure 5 is a perspective view of the protecting hood or cap.

Referring now more particularly to the accompanying drawing, in which like numerals designate like parts throughout the several views, the numeral 5 represents a mounting member provided with a longitudinal bore 6 extended inwardly from its outer end 7 and terminating short of its inner end to provide a shoulder 8.

A lock cylinder 9 having a plurality of conventional tumblers 10 is mounted in the longitudinal bore 6 of the mounting member, and is movable from a locked position upon the insertion of a key 11 which retracts the plungers 10 within the periphery of the cylinder 9 in the customary manner. When the cylinder is in locked position, the plungers are urged into a longitudinal groove 12 and when moved to its unlocked position, which in the present instance is 90 degrees from the locked position, the lower ends of the plungers are aligned with the second longitudinal groove 13 to permit the removal of the key 11.

The innermost end of the cylinder 9 is reduced in diameter, as at 14, to extend through the reduced bore at the innermost end of the bore 6 with its end flush with the end of the mounting member; and at one point in the periphery of the reduced diameter 14 a stop 15 is formed which extends to the diameter of the major portion of the lock cylinder, and moves in a cut away portion 16 in the shoulder 8 to abut the ends thereof at the limits of rotation of the lock cylinder.

An annular groove 17 is formed in the outer periphery of the mounting member, and that portion of the mounting member between the groove and its outermost end is of less diameter than the inner portion thereof, being sub-

stantially the same as that of an enlargement or head 18 formed on the outermost end of the lock cylinder 9 whose inner periphery forms a shoulder 19 which engages the end of the 5 mounting member when the cylinder is inserted therein. The outer face of the enlargement or head 18 is provided with a substantially elliptical shaped projection 20 whose longitudinal axis aligns with that of the key 10 opening 21 in the lock cylinder and whose outer ends terminate in substantially circular pins 22.

Enclosing the elliptical shaped projection 20, the head or enlargement 18 and the adjacent portion of the mounting member is a protecting hood or cap 23, which is pressed from bendable metal hardened sufficiently to withstand destruction by chipping and the like. The closed, outermost end of the protecting 20 hood, which is apertured, as at 24, to permit the insertion of the key 11 into the lock cylinder, is formed to substantially the contour of the projection 20 and the pins 22, as best illustrated in Figure 5, to constitute a handle by 25 which the cylinder may be turned independent of the key 11, and the innermost end of the hood projects over the mounting member to abut the innermost wall 25 of the annular slot 17. The inner diameter of the hood is such as 30 to snugly receive the enlargement 18 and the adjacent outermost end of the mounting member, and the outer diameter thereof is substantially the same as the major portion of the mounting member so that it forms substantially 35 a continuation thereof.

The hood member and consequently the lock cylinder received therein is maintained assembled with the mounting member in the following manner. A plurality of openings 40 26 are formed in the hood member adjacent its inner periphery at spaced intervals about its diameter and the metal 27 between the openings 26 and the innermost periphery of the hood, which lays directly over the annular 45 groove 17, is clinched or pressed inwardly into the groove to freely rotatably secure the hood against detachment from the mounting member. It will be noted that the portions 27 are provided with a rounded medial projection 50 28 which engage the outermost wall of the annular groove and facilitate free rotation of the hood with respect to the mounting member.

From the foregoing description taken in 55 connection with the accompanying drawing, it will be readily apparent to those skilled in the art to which an invention of the character described appertains, that I provide a novel means for protecting a lock cylinder against 60 destruction and for securing the same against detachment from its mounting member, which positively prevents removal of the lock cylinder without first removing the hood, in which removal of the hood is impossible by 65 tools inserted into the key opening, and which

is so shaped as to provide a handle whereby the lock cylinder may be turned independent of the key.

What I claim as my invention is:

1. In a lock device, a mounting member, a lock cylinder rotatable in the mounting member, an enlargement formed on the lock cylinder, a cap member enclosing the enlargement of the lock cylinder, a stop formed on the mounting member, and clinched portions 70 formed in the cap member and engaged with the mounting member stop to prevent longitudinal movement of the lock cylinder but permit rotation thereof.

2. In a lock device, a mounting member, a lock cylinder rotatable therein, an enlargement formed on the outer end of the lock cylinder, a stop formed on the mounting member, a cap member enclosing the enlargement formed on the lock cylinder and shaped to 80 conform to the contour thereof whereby it is rotatable with the lock cylinder, and means pressed inwardly from the cap member and engaged with the mounting member stop to maintain the lock cylinder and cap member 85 freely rotatably assembled with the mounting member.

3. In a lock device, a mounting member, a lock cylinder rotatable therein, a projecting enlargement formed on one end of the lock cylinder, a cap enclosing the lock cylinder enlargement and the adjacent portion of the mounting member, and means connecting the cap with the mounting member to maintain the lock cylinder and cap assembled with the 100 mounting member.

4. In a lock device, a mounting member having an annular groove, a lock cylinder rotatable in the mounting member, a cap enclosing the outer end of the lock cylinder and the adjacent portion of the mounting member, and means carried by the cap and engaged in the annular groove whereby longitudinal movement of the lock cylinder and cap with respect to the mounting member is 105 prevented.

5. In a lock device, a mounting member having an annular groove, a lock cylinder rotatable in the mounting member, a cap enclosing the outer end of the lock cylinder and the adjacent portion of the mounting member, and pressed-in portions carried by the inner end of the cap and engaged in the mounting member annular groove whereby the parts are maintained against disassembly 115 but permitted rotation.

6. In a lock device, a mounting member having an annular groove, a lock cylinder rotatable in the mounting member, a cap enclosing the outer end of the lock cylinder and the adjacent portion of the mounting member and having an opening adjacent its inner end, and the material between the opening and the innermost periphery of the cap being 120 pressed downwardly into the mounting mem- 125

- ber annular groove to permit rotation of the cap and lock cylinder but to prevent longitudinal movement thereof with respect to the mounting member.
5. 7. In a lock device, a mounting member, having an annular groove, a lock cylinder rotatable in the mounting member, and a cap pressed from hardened bendable metal and enclosing the outer end of the lock cylinder
- 10 and the adjacent portion of the mounting member and having openings adjacent its inner end, the metal extending between the openings and the said inner end of the cap being pressed into the mounting member and annular groove to prevent separation of the cap and mounting member and to protect the lock cylinder against destruction.
- 15 8. In a lock device, a mounting member having an annular groove, a lock cylinder rotatable in the mounting member, a cap enclosing the outer end of the lock cylinder and extending over the annular groove and having openings adjacent its inner end, the metal between the inner end of the cap and the openings being clinched inwardly to project into the annular groove, and means formed on the clinched-in portions to facilitate rotation of the cap about the mounting member.
- 20 9. In a lock device, a mounting member, a lock cylinder rotatable therein, an enlargement formed on the outer end of the lock cylinder and having an irregular shape, a cap enclosing the lock cylinder enlargement and correspondingly shaped whereby the irregular shape of the cap provides convenient means for turning the lock cylinder, and means connecting the cap with the mounting member to prevent separation thereof.
- 25 10. In a lock device, including a mounting member and a lock cylinder rotatable therein, a protecting hood of hardened metal enclosing the outer end of the lock cylinder and mounting member to prevent destruction of the lock cylinder, said protecting hood being formed so as to provide a handle to facilitate rotation thereof, and means connecting the protecting hood with the mounting member
- to maintain it and the lock cylinder assembled with the mounting member.
11. In a lock device, a mounting member formed with a support engageable body portion and a projecting end, a lock cylinder movable in said mounting member, a cap positively connected with the outer end of said lock cylinder and rotatable over the entire projecting end of the mounting member, and a hand grip portion formed on said cap.
12. In a lock device, a mounting member, a lock cylinder rotatable therein having means for locking said cylinder from rotation, and means for rotating said cylinder to locked position independently of a key, said means including a protecting hood covering the exposed portions of the lock.
13. In a lock device assembly including a mounting member with a lock cylinder mounted therein, a cap projecting from the front face of the assembly to form a handle for turning purposes positively connected with the cylinder and rotatably connected with the mounting member.
14. In a lock device, a mounting member, a lock cylinder movable therein to unlocked position by a key, manually operable means connected with the cylinder for moving said cylinder to locked position independently of a key, and said manually operable means having connection with the mounting member to maintain the parts completely assembled.
15. In a lock device, a mounting member, a lock cylinder movable therein to an unlocked position by a key, manually operable means connected with the cylinder for moving said cylinder to locked position independently of a key, said manually operable means being shaped as a cover for exposed portions of the lock, and said manually operable means being arranged to maintain the parts completely assembled.

In testimony whereof I have hereunto affixed my signature.

EDWARD N. JACOBI.
